Primary Examiner — Terry A Wallace(74) *Attorney, Agent, or Firm* — Scott H. Kaliko, Esq;
Kaliko & Associates, LLC(57) **CLAIM**

The ornamental design for a anti spill cup holder drink coaster, as shown and described.

DESCRIPTION

FIG. 1 is a perspective view of the anti spill cup holder drink coaster showing my new design.

FIG. 2 is a perspective view thereof.

FIG. 3 is a perspective view thereof.

FIG. 4 is a front view thereof.

FIG. 5 is a rear view thereof.

FIG. 6 is a left side view thereof.

FIG. 7 is a right side view thereof.

FIG. 8 is a top plan view thereof.

FIG. 9 is a bottom plan view thereof.

FIG. 10 is an exploded perspective view thereof; and,

FIG. 11 is a perspective view thereof.

The broken lines showing a cup and glass are for illustrative purposes only and form no part of the claimed design.
